MEANS FOR PROPORTIONING PULL TO SPECIMEN SIZE

Filed July 16, 1945

Fig. 1.

UNITED STATES PATENT OFFICE

2,493,836

MEANS FOR PROPORTIONING PULL TO
SPECIMEN SIZE

David C. Scott, Providence, R. I., assignor to
Henry L. Scott Company, a corporation of
Rhode Island

Application July 16, 1945, Serial No. 605,389

1 Claim. (Cl. 73—90)

1

This device relates to a testing machine, more particularly of the inclined plane type.

In order that comparative tests may be provided in a testing machine uniform specimens must be provided. For instance, in comparing tests on rubber threads, specimen threads of a uniform cross sectional dimension must be had. If specimens of non-uniform dimension are tested, then some compensation must be made by calculation if comparative curves or graphs are to be provided.

One of the objects of this invention is to provide a means so that different cross sectional test specimens may be used in the machines and yet comparative results will be indicated directly on the platen or recording means as the tests are made with no mathematical computation necessary to reduce the test data to a uniform standard.

Another object of this invention is to adjust the pull which is applied to the specimen so as to cause this pull to be proportional to the cross section of the specimen according to a predetermined schedule.

Another object of this invention is to provide an easily manually adjustable weight applying means to provide the proper mass.

With these and other objects in view, the invention consists of certain novel features of construction, as will be more fully described and particularly pointed out in the appended claim.

In the accompanying drawings:

Fig. 1 is an elevation of a testing machine equipped with this invention;

Fig. 2 is a perspective view of the carriage which applies the pull to the specimen;

Fig. 3 is a perspective view of one of the weights which is assembled with the carriage; and

Fig. 4 is a perspective view of a different weight which is assembled with the carriage.

In proceeding with this invention I utilize the inclined plane type of testing machine which has heretofore been known, and provide a new form of carriage therefor which is equipped with a plurality of weights which may be readily manually removed that the proper carriage mass may be had. In this manner I may cause the weight of the carriage which applies tension to the specimen to be adjusted in accordance with the cross sectional dimension of the specimen according to a predetermined calculation and thus the record which is mechanically formed in the machine will be comparative for all specimens even though they be of varying cross sectional dimensions.

With reference to the drawing 10 designates a

base having a standard 11 extending upwardly therefrom and pivotally supporting on the shaft 12 at the upper end of this standard 11 an inclinable beam designated generally 13.

The beam 13 is provided with four rollers 14, 15, 16, and 17 which are grooved to receive and slidably mount a platen 18 which is provided with a clamp 19 for holding a chart or the like in position thereon. A drum 20 in the rear of this platen 18 has a flexible element 21 wound thereon which element extends over a pulley 22 rotatably mounted at 23 on the beam and which element is anchored to some part fixed to the base 10. In this manner as the beam swings about its pivot 12 the platen 18 will be moved relative to the beam by sliding along the roller mounting. The beam 13 has at one end a roller 26 which rests upon a horizontal support 27 from which extends a rack 28 which engages with a pinion so that the same will be lowered in response to the operation of a motor 29 operating through gears in box 30 and controlled as to reversing by the handle 31 and as to operation by the clutch handle 32.

The beam also carries a track 25 on which is mounted a specimen clamp 33 operated through an eccentric 34 having handle 35 so as to grip a specimen 36 and hold it in fixed relation to the beam. Also mounted on this track is a carriage 30 designated generally 37, which has a pair of wheels 38 and 39 resting on the track with axles extending into the bearings 40 and 41 for the wheel 39 and 42 and 43 for the wheel 38. The carriage has an end plate 44 upon which a specimen clamp 45 having eccentric 46 and handle 47 is mounted for clamping the other end of specimen 36. Depending from the framework 48 in which the bearings 40 to 43 are provided, there is a frame 49 of generally rectangular shape having end walls 50 and 51, a top wall 52 and a bottom wall 53 with intermediate shelves 54 and 55. On the three shelves 53, 54, and 55 I provide a plurality of weights 56. Three weights may be positioned on each of the shelves such

as indicated in Fig. 1, the handle portion 57 serves as a convenient means for removing the weights from the shelves as desired. A supporting rod 58 extends downwardly from the frame 49 and then horizontally as at 59 to support weights 60 by means of openings 61 therein. Weights 60 are in a number sufficient to supply weight to the carriage in fractional amounts of the weight 56. Thus, by means of a plurality of weights 56 and 60 the desired mass may be provided for the carriage 37 so as to adjust its weight

according to the cross sectional dimension of the specimen to be tested in accordance with a predetermined calculation which may be worked out for each type of material or specimen to be tested. The weight 60 may be of different values as shown at 60a, 60b, and 60c, Fig. 1.

In order to compensate or counterweight for the mass of the beam, at the left-hand side of the pivot 12, I provide a rod 65 having a weight 66 thereon which may be positioned along the rod 65 in varying distances from the pivot to be then held in position by the set screw 67.

In the testing of rubber thread the cross sectional area of the thread to be tested is usually measured in square mills. The weight of the carriage alone without any weights 56 or 60 will be calculated for the smallest square mill area of a specimen which is likely to be provided for testing. Should the square mill area of the specimen tested be greater than this smallest area then additional weights will be required on the carriage, where this smallest area is to be the standard of comparison. The carriage is usually 100 grams. The weights 56 and 60 are usually marked in square mills and the arrangement is such that if the area of the specimens to be tested is 45 square mills greater than the standard of comparison then weights marked to 45 square mills will be placed upon the carriage in addition to its weight. Such weights 56 and 60 which will figure up to 45 square mills will be placed on the shelves or hung upon the hook 59. If 54 square mills was the area of the specimen to be tested, then in addition to the 45 square mills, 9 additional square mills will be used by selecting weights such as 60a or 60b marked according to a predetermined

marking for this purpose. In this way the square mills of any specimen may be made up by weighting the carriage correspondingly thereto by picking out weights in accordance with the dimension or area of the specimen to be tested and all readings on the chart placed on the platen 18 will thus be comparable and markings may be mechanically applied to the chart such for instance as by a marker 65' carried by the carriage as shown in Fig. 1.

I claim:

A testing machine comprising an inclinable beam, a clamp carried by the beam for securing one end of a specimen, a carriage movable along the beam as the same is inclined, means for securing the other end of a specimen to said carriage, said carriage comprising a plurality of separate superimposed open-ended compartments for the reception of weights and separable weights for said compartments to adjust the effective mass of the carriage.
